SAFETY FLAG FOR A BICYCLE

John B. Baker, Medina, Wash.
(P.O. Box 368, Issaquah, Wash. 98027)

Filed Sept. 7, 1973, Ser. No. 395,232

Term of patent 7 years

Int. Cl. D29—02

U.S. Cl. D10—109

FIG. 4

FIG. 5

FIG. 6

FIG. 1 is a perspective view of a safety flag for a bicycle showing my new design, the bicycle being shown in broken lines for illustrative purposes only;

FIG. 2 is an outside elevation view on an enlarged scale of the safety flag as locked in a non-using position;

FIG. 3 is a plan view on an enlarged scale of the safety flag as locked in a non-using position;

FIG. 4 is an inside elevation view on an enlarged scale of the safety flag as locked in a non-using position;

FIG. 5 is a front elevational view on an enlarged scale of the safety flag in an outstretched position; and,

FIG. 6 is a rear view on an enlarged scale of the safety flag in an outstretched position.

I claim:

The ornamental design for a safety flag for a bicycle, substantially as shown and described.
